UNITED STATES PATENT OFFICE.

JAMES H. DENNEDY, OF DETROIT, MICHIGAN.

COMPRESSOR.

Application filed December 10, 1921. Serial No. 521,426.

To all whom it may concern:

Be it known that I, JAMES H. DENNEDY, a citizen of the United States, residing at Detroit, county of Wayne, State of Michigan, have invented a certain new and useful improvement in Compressors, and declare the following to be a full, clear, and exact description of the same, such as will enable others skilled in the art to which it pertains to make and use the same, reference being had to the accompanying drawings, which form a part of this specification.

This invention relates to compressors and the object of the invention is to provide an improved discharge valve for a compressor which is entirely automatic in operation and of comparatively cheap construction. A further object of the invention is to provide a discharge chamber for a compressor containing the discharge valves for the cylinders of the compressor, the said chamber also having a discharge port and being provided with baffles between the discharge ports for the cylinders and discharge port for the chamber. Another object of the invention is to provide a quick action discharge valve for compressors embodying a leaf spring adapted to automatically open at a certain pressure and automatically and rapidly close when the pressure is decreased. A still further object of the invention is to provide a discharge valve for a compressor adapted to retain a quantity of oil about the discharge valves, the said oil being blown away from the valves during discharge of the air and the said oil aiding in sealing the discharge valves when closed and preventing ingress of air into the cylinders. These objects and the several novel features of the invention are hereinafter more fully described and claimed and the preferred form of construction by which these objects are attained is shown in the accompanying drawings in which—

Fig. 1 is a section through a compressor provided with a discharge chamber and discharge valves embodying my invention.

Fig. 2 is an enlarged section through one of the discharge valves and adjacent portions of the discharge chamber.

Fig. 3 is a plan view of the discharge valves.

Fig. 4 is a reduced section taken on line 4-4 of Fig. 2.

The compressor as shown in Fig. 1 comprises a crank case 1 in which a crank shaft

2 is rotatably mounted. A pair of connecting rods 4 are provided each having a bearing on the crank shaft 2 and each being connected at the upper end to a piston 5. 60 These pistons 5 are reciprocably mounted in a pair of cylinders 6 within a casing 7 to which an air intake line is connected, the said casing providing a chamber 8 through which air may pass to the intake ports 9 of the cylinders. The pistons 5 are each provided with an automatic valve and are fully described and claimed in another application, Serial No. 521,426, filed by me December 10, 1921. These pistons on the upward 70 stroke are adapted to close the piston valve and compress the air within the cylinder and on the downward stroke are adapted to open the piston valve and admit fresh air into the cylinder. A plate 10 is provided across the upper end of the cylinders and is secured in place between the head or discharge chamber 11 of the compressor and the casing 7 by bolts 12. This plate 10 is provided with an aperture 13 centrally over each cylinder and a valve member 14 is made a press fit in each aperture, the said members 14 being each provided with a flange 15 limiting the extent of insertion thereof into the apertures 13. Each member 14 as shown in Fig. 2 is provided with an upper face which is ground on a radius to provide a valve seat. The discharge valve consists of three leaves 16, 17 and 18, the leaf 16 being the shortest, the leaf 17 being longer and the leaf 18 being the longest as shown in Fig. 3. The leaves 16 and 17 are spring steel and the leaf 18 is phosphor bronze and is provided with a ground lower face adapted to fit the ground face of the member 14. Each of the spring leaves 16, 17 and 18 as shown in Fig. 3 are provided with a notch 19 on one side and notch 20 on the opposite side to receive the bolts 21 and 22 shown in Fig. 4 which hold the leaves in alignment. A cross member 23 is positioned beneath the leaves to provide a seat therefor and a cross member 24 is positioned over the same and the bolts 21 and 22 are inserted through apertures provided in the ends of the cross members 23 and 24 and are threaded into the plate 10 as shown in Fig. 4, the shafts of the bolts 21 and 22 engaging in the notches 19 and 20 of the spring leaves. In this manner the leaves are 110 bindingly secured together at the center and the ends thereof extend over the discharge

apertures 25 provided in the member 14. The upper ends of the members 14 and the upper face of the member 23 are all ground on a common radius and the spring leaf 18 which is phosphor bronze is adapted to seat on the members 23 and 14 and close the discharge apertures for the cylinders. When the leaf 18 is secured in place the members 14 deflect the ends of the said leaf upwardly so that the leaf is always under an initial tension which causes it to close rapidly after being opened. The leaves 16 and 17 are so proportioned that the pressure which they exert on the leaf 18 causes it to take the form of a true arc and thus closely fit the arcuate valve faces on the members 14 and provide a practically leak proof valve. A series of baffles are provided in the head or discharge chamber of the compressor comprising a baffle 26 on each side and a baffle 27 in the center having an opening 28 therethrough, the discharge or pressure line 29 being connected to the discharge chamber by means of a member 30. During operation of compressors of this type a slight amount of oil is usually carried upwardly from the crank case by the pistons and is pumped into the head 11 with the air passing through the discharge valves. The air in passing about the baffles 26 and 27 tends to deposit the oil on the said baffles and due to the shape of the baffles, the oil will drain onto the plate 10 and about the discharge valves as indicated at 31 in Fig. 1. This quantity of oil acts as a seal for the discharge valves preventing air from entering the cylinder through the discharge valves when closed.

In operation the crank shaft 2 is rotated which imparts a reciprocating motion to the connecting rods and by means of the connecting rods 4 the pistons 5 are reciprocated. Upon each upward stroke of the pistons the air in the cylinders 6 is compressed until sufficient to overcome the resistance of the spring leaves 16, 17 and 18 of the discharge valves, thus opening the discharge valves and allowing the compressed air to pass through the apertures 25 and through the discharge chamber 11 into the discharge line 29. As the discharge valve is opened the compressed air blows the oil away from the openings 25 so that the oil does not return to the cylinders and, when the discharge valve is closed during the downward stroke of the piston, the oil acts as a seal preventing leakage of air about the discharge valve. On the downward stroke of the piston the piston valve is opened as shown at the left of Fig. 1 allowing fresh air to enter the cylinders 6 by the vacuum produced therein

and on the next upward stroke of the piston the piston valve is closed as shown at the right of Fig. 1 and the air is compressed in the cylinder and discharged through the discharge line. While I have shown a compressor composed of two cylinders it is to be understood that this construction may be duplicated as many times as desired to produce a compressor comprising a greater number of cylinders and consequent greater capacity.

From the foregoing description, it becomes evident that the device is very simple and efficient in operation, is entirely automatic, is of cheap construction and consequent low manufacturing cost, will not get out of order and provides a device which accomplishes the objects described.

Having thus fully described my invention, its utility and mode of operation, what I claim and desire to secure by Letters Patent of the United States is—

1. The combination in a compressor of a pair of spaced cylinders for reciprocably mounting their respective pistons, a plate constituting a common closure for the ends of said cylinders, spaced discharge apertures in said plate for the respective cylinders, an annular boss disposed in each of said apertures and detachably but non-rotatably secured to said plate, said bosses constituting discharge passages for said cylinders and having their faces ground on a common curve, a plurality of spring leaves forming a laminated valve for co-operating at their ends with said faces to close said passages, and means for clamping said leaves intermediate their ends to said plate for holding said laminated valve under tension against said faces.

2. In a discharge valve for compressors, the combination of a pair of spaced valve seats constituting passageways for the fluid compressed, said seats being concave on a common curve, a plurality of leaf springs disposed on said seat, that nearest the seat constituting at its respective ends the valve closure for said seats, a pair of spaced screws extending at the respective sides of said springs and intermediate their ends, said leaves at their respective sides being provided with slots along which portions of said screws extend for preventing longitudinal and transverse movement of said leaves, and a clamping member co-operating with said screws to clamp said leaves against said seats.

In testimony whereof I sign this specification.

JAMES H. DENNEDY.
